United States Patent Office.

ORRIN A. WHEELER, OF DONIPHAN, KANSAS.

Letters Patent No. 98,213, dated December 21, 1869.

IMPROVEMENT IN SEED-DRILLS.

The Schedule referred to in these Letters Patent and making part of the same.

To all whom it may concern:

Be it known that I, ORRIN A. WHEELER, of Doniphian, in the county of Doniphan, and in the State of Kansas, have invented certain new and useful Improvements in Seed-Drills; and do hereby declare that the following is a full, clear, and exact description thereof, reference being had to the accompanying drawing, making a part of this specification, in which—

Figure 1 is a rear elevation of my improved device; Figure 2 is a vertical cross-section of the same, on the line $x x$ of fig. 1;

Figure 3 is a plan view of the upper side of the seed-box or hopper;

Figures 4 and 5 are cross-sections of the same, on lines $y y$ and $z z$ of fig. 3; and

Figure 6 is an enlarged portion of the adjustable bottom of said seed-box.

Letters of like name and kind refer to like parts in each of the figures.

My invention belongs to a class of devices termed seed-drills; and

It consists principally in the means employed for raising and lowering the drills, and regulating the depth of the same, and in combination therewith, for throwing the seed-wheel shaft in or out of gear.

It also consists in the means employed for regulating the quantity of grain sown, as is hereinafter fully described.

In the annexed drawing—

A and A' represent the ground-wheels, suitably journaled upon the ends of a metal axle, B, which, immediately inside of each wheel, extends upward at a right angle to the journals, and then across, parallel with the same, so as to form upon either end of said axle a crank.

Suspended from the central portion of the axle B is the drill-frame, composed of two strips, C and C', placed parallel with each other and with said axle, and secured together by means of two or more cross-pieces D.

The drill-shares E are attached, at their front ends, to the strip C, and from thence curve downward and rearward beneath the rear strip C', to which each is connected by means of a support, F.

G represents a seed-box or hopper, of the usual form, resting upon and secured to the strip C', in which a shaft, H, provided with the requisite number of seed-wheels h, is suitably journaled.

A semicircular cavity, i, corresponding in length to the seed-wheels, is cut beneath each, in the bottom of the hopper I, and in the bottom of each cavity is provided a round hole, i', opening into the seed-tubs K, which, being connected at their upper ends to said hopper, extend downward, and are se-

cured, at their lower ends, to the rear ends of the drill-shares.

As thus constructed, the seed is carried into the cavities i by the seed-wheels, and from thence drops through the openings i' into the seed-tubes, and is deposited within the furrow made by the drill, and it will be readily seen that the quantity sown will be governed by the capacity of said openings i'.

In order that the size of the openings i' may be varied, as desired, a false bottom or slide, L, is placed immediately beneath the real bottom I, and so arranged as to move freely lengthwise of the hopper.

Cam-shaped openings, l, are provided in said slide, immediately beneath, and corresponding with the openings i' in the bottom, which, when said slide is placed as shown in fig. 3, do not obstruct the free passage of the grain; but if it be moved to the right, the size of the openings contained therein with relation to those in the bottom, will be correspondingly decreased, and the flow of the grain obstructed.

The adjustment of the slide is effected by means of a lever, M, pivoted to the rear side of the hopper, and connected, at its lower end, with the rear edge of said slide.

The upper end of the lever M, being pointed, serves as an index-finger, and indicates, upon the arc or scale m, the degree of adjustment of said slide, and consequently the quantity of grain being sown.

Secured to, and projecting upward from the axle B, near its centre, lengthwise, is a lever, N, by means of which said axle may be partially revolved, and the devices suspended therefrom correspondingly raised or lowered.

An arc or quadrant, O, attached to the strip C, and to the seed-box G, and provided with a series of notches for the reception of said lever, furnishes a means by which the latter is locked in place when the drills are adjusted to the desired height.

Motion is imparted to the seed-wheel shaft H, by means of a gear-wheel, P, secured to and revolving with the hub of the wheel A', and meshing with the teeth of a pinion, R, attached to the end of said shaft.

As, however, it is necessary that the seeding-devices should be operated only when the drills are furrowing the ground, the parts of the machine are so adjusted as to bring said gear and pinion into engagement with each other at such times, so that when said drills are raised, the seeding-devices are at the same time thrown out of gear, whereby the heretofore separate operations required, in order to produce this result, are avoided, and greater convenience and ease in the management of the drill secured.

Having thus fully set forth the nature and merits of my invention,

What I claim as new, and desire to secure by Letters Patent, is—

The means employed for elevating or lowering the drills, and for throwing in or out of gear the seeding-devices, consisting of the crank-axle B and lever N, and, in combination therewith, the quadrant O, or its equivalent, substantially as and for the purpose specified.

Also, the arrangement of the slide L, provided with

the cam-shaped opening I, the bottom I, and the lever M, substantially as and for the purpose shown.

In testimony that I claim the foregoing, I have hereunto set my hand and seal, this 30th day of August, 1869.

ORRIN A. WHEELER. [L. S.]
